Fig. 10

FIG. 1 is a perspective view of a base for a telephone set showing one embodiment of our new design wherein a rotary dial is used;

FIG. 2 is a top plan view of the form shown in FIG. 1;

FIG. 3 is a side elevational view of the form shown in FIG. 1, the opposite side being substantially similar in form;

FIG. 4 is a perspective view of a base for a telephone set showing another embodiment of our design wherein a pushbutton dial is used;

FIG. 5 is a top plan view of the form shown in FIG. 4;

FIG. 6 is a side elevational view of the form shown in FIG. 4, the opposite side being substantially similar in form;

FIG. 7 is a perspective view of a base for a telephone set showing another embodiment of our new design;

FIG. 8 is a top plan view of the form shown in FIG. 7; and

FIG. 9 is a side elevational view of the form shown in FIG. 7; and

FIG. 10 is a rear elevation view of the bases of the forms as illustrated in FIGS. 1, 2 and 3; FIGS. 4, 5 and 6; and FIGS. 7, 8 and 9.

A typical handset and cord intended for use with, but not forming a part of, the base for a telephone set are shown in dashed outline in FIGS. 1, 4 and 7.

We claim:

The ornamental design of a base for a telephone set, substantially as shown and described.
